UNITED STATES PATENT OFFICE.

LOUIS B. STEINIGER, WILLIAM M. REESE, AND MERL W. REESE, OF OMAHA, NEBRASKA, ASSIGNORS TO GRIP BOW TIE COMPANY, OF OMAHA, NEBRASKA.

BOW TIE.

Application filed December 15, 1922. Serial No. 607,103.

To all whom it may concern:

Be it known that we, LOUIS B. STEINIGER, WILLIAM M. REESE, and MERL W. REESE, citizens of the United States, residing at Omaha, in the county of Douglas and State of Nebraska, have invented a certain new and useful Improvement in Bow Ties, of which the following is a full, clear, concise, and exact description, reference being had

10 to the accompanying drawings, forming a part of this specification.

Our invention relates to ties and more particularly to bow ties and has to do with the provision of a new and improved shaping frame, an object being to provide a simplified device of this character which is cheap to manufacture, easily assembled with the usual bow tie, and effective in use.

In the ordinary cloth bow tie, the tie is made up in a standard shape which it retains. Various shaping frames have heretofore been used but have certain objections, being either too expensive to manufacture, or too difficult and expensive to insert in

20 the tie.

Our improved frame and tie overcomes these various objections.

For a better understanding of our invention references is to be had to the accompanying drawing in which

Figure 1 is a face view of a bow tie embodying our invention;

Fig. 2 is a top view of Fig. 1, the dotted lines indicating various forms the tie may be shaped into;

Fig. 3 is a face view of the shaping element of the tie attached to the filler or backing strip;

Fig. 4 is a face view of the shaping element; and

Fig. 5 is an enlarged right end view of Fig. 4.

Referring more in detail to our invention as illustrated, we show a bow tie A of ordinary cloth construction but with our im-

proved shaping frame B added thereto. This frame is preferably made up of a flexible metal element in the form of a wire 5 suitably secured between fastening elements 6-7, preferably paper pasted together with the wire 5 held thereby. This wire is such that it may be readily bent into various angles. The frame B is then preferably fastened to a lining or backing 8 which is usually made of cotton wadding. To fasten the element B to the backing 8 we preferably sew the parts together as indicated at the dotted lines 9. This is a cheap and effective way of assembling the parts.

The complete insert, that is the metallic 60 reinforced shaping element B and the backing or filler 8 are then built into the tie as it is made up, this being indicated by the dotted lines in Fig. 1.

The tie may now be shaped as desired by 65 bending the wings back against the collar, away from the collar or straight across, as indicated by the full and dotted lines in Fig. 2. Also it will be apparent, that the wings may be bent up or down if desired. In fact, 70 they may be readily placed at almost any angle where they will remain until changed according to the will of the wearer.

What we claim as new and desire to secure by United States Letters Patent is:

The combination with a bow tie, of a shaping insert built into the tie as it is made up, said insert including a straight pliable wire strip, two paper fastening facings secured together over said strip, and a filler 80 or backing to which said facings are sewed to form a unit insert shaped to be held in the tie, said wire strip and paper facings being readily bendable so as to permit moving the tie wings into various angular positions as desired.
